M. C. FOX

LAMP CLOCK

Filed March 18, 1924

Inventor

Maud C. Fox

By

Attorney

UNITED STATES PATENT OFFICE.

MAUD C. FOX, OF BROOKLYN, NEW YORK.

LAMP CLOCK.

Application filed March 18, 1924. Serial No. 700,090.

To all whom it may concern:

Be it known that I, MAUD C. Fox, a citizen of the United States, residing at New York city, borough of Manhattan, in the county of New York and State of New York, have invented new and useful Improvements in Lamp Clocks, of which the following is a specification.

This invention relates to illuminated 10 clocks, and proposes the construction of a clock having the face dial lighted from within by electric lamps or other source of illumination.

The necessity for having the lamps be- 15 tween the clock movement and face dial in order to avoid the appearance of shadows upon the face dial gives rise to the problem of rendering the lamps readily accessible for the purpose of changing them, the solution 20 of which problem is the principal object of the present invention.

Another object of the invention is the provision of means for winding the clock from the front without marring the illuminated 25 face dial by unsightly winding stems and key-holes.

A more specific object of the invention is to slidably mount the movement, lamps and 30 face dial relatively to the clock case, and in fixed spaced relation to each other, so that they may be drawn out a sufficient distance to give convenient access to the winding key and lamps through the space vacated by the face dial.

With the above and other objects in view, 35 my invention consists in the improved illuminated clock illustrated in the accompanying drawings, described in the following specification, and particularly claimed, and in such variations and modifications thereof 40 as will be obvious to those skilled in the art to which my invention relates.

In the drawings accompanying and forming 45 a part of this specification, and wherein in the preferred embodiment of my invention is illustrated:

Figure 1 is a front elevation of a practical embodiment of my invention.

Figure 2 is a section taken along the line 50 2—2 of Figure 1.

Figure 3 is a plan view.

Referring now in detail to the several figures, the numeral 1 represents the clock casing which may be of any configuration 55 and is hollow, providing a space 2 for the normal reception of the clock-works 3, the

lamp or lamps 4 and the electrical connections 5 leading to said lamps. The lack of the casing is preferably closed by means of a rear wall 6 having a suitable opening 60 7 through which the electric conduit 8 passes. It is not necessary, however, that the electrical connections should enter the clock from the rear since the invention does not concern itself particularly with the 65 means by which the current is brought to the lamps. The front of the clock casing, as shown, is formed with an opening having a rabbeted edge 9 within which the bezel 10 fits in a dust-tight manner. A dial 11, 70 which is preferably of translucent material is supported by the bezel. The dial is perforate in the center to permit the outer end of the hand sleeve 12 to project there- 75 through, the hands being positioned, in the illustrative example of the invention on the outside of the dial, the hand 13 being fixed to the sleeve 12 and the hand 14 to the usual stem 15 which extends through said sleeve. The clock numerals are inscribed 80 upon the dial adjacent the periphery of the latter. It is to be understood that the scope of the invention by no means limits the hands to a location exteriorly of the dial.

The bezel 10 is fixed to a carriage 16 which is slidably mounted within the block cas- 85 ing. Said carriage may be of any suitable construction, being here shown as comprising parallel rods 17 each fixed at one end to the bezel and extending rearwardly with- 90 in the clock casing, the rear ends of said rods being held together by a rectangular frame 18. The two bottom rods, which are in a horizontal plane, are bridged over by cross pieces 19 and 20 forming supports re- 95 spectively, for the clock-works 3 and the lamp sockets 21. An operating handle 22 for sliding the carriage 16 extends through the front of the clock casing and is secured at its rear end to the carriage or one of the 100 objects mounted thereupon, preferably back of the center of mass of said carriage so as to prevent a tilting movement of the carriage that might cause binding of the same in the casing. By pulling the operating handle outwardly, the carriage, including the bezel, lamps and clockworks is project- 105 ed from the front of the clock casing. The range of its outward movement is limited by the abutment of the angular portion 23 of the operating handle against the front of the clock casing. Any other means for lim-

iting the movement of the carriage so as to prevent it falling out of the front of the clock casing may be substituted for that herein shown without departing from the scope of the invention.

In an illuminated clock of the character described and illustrated it is necessary that the lamps be positioned between the clock movement and the hands of the clock in order to prevent the casting of a shadow of the movement upon the dial. This would ordinarily make it quite inconvenient to have access to the lamps for purpose of replacement from the back of the clock, for the clock-works are in the way. It would also generally be impossible to reach the lamps from the front of the clock without taking off the hands. To avoid these difficulties I have provided the slideable carriage to support the clock-works, lamps and face dial in fixed spaced relation so that, by pulling upon the handle 22, the carriage comes out, the lamps and clock-works assuming the position at the front of the clock casing indicated in dotted lines in Figure 2, being readily accessible through the space vacated by the bezel and face dial in their forward movement. When the parts are in projected position the lamps may be removed and replaced without inconvenience and the handle 22 then pressed toward the casing to restore the parts to their original position.

It is quite inconvenient to wind an electrically illuminated clock from the rear on account of the presence of the electrical connections which are apt to become disarranged when the clock is bodily shifted away, for the purpose of winding, from the wall against which it usually rests. It is also undesirable to wind the clock from the front in the ordinary manner by means of winding stems and key-hole bushings extending through the dial, because the illuminated character of the latter would make such construction unsightly. I have therefore devised means for winding the dial, by arranging a key 24 on the forward side of the clock-works, said key being in the dotted line position shown in Figure 2 when the carriage is extended. To wind the clock, it is necessary merely to pull on the handle 22 until the carriage comes out of the casing, then to reach behind the dial and between the dial and clock casing for the winding key. After the clock has been wound the handle 22 is pushed toward the casing until the bezel engages its dust-proof seat in the latter, the clock then having the appearance of being keyless.

Although I have thus described the preferred embodiment of my invention, it is evident that those skilled in the art may make various changes in the construction, combination and arrangement of the several parts without departing from the spirit and

scope of the invention and I accordingly reserve the right of adopting all such legitimate changes.

Having described my invention what I claim as new and desire to secure by Letters Patent, is:—

1. A clock including a casing, a slidably supported movement having a forwardly directed winding key, said movement and key being normally housed within said casing, and means for sliding said movement a sufficient distance to present the key adjacent the exterior of said casing. 75

2. A clock including a casing apertured at one side, a carriage within said casing mounted to slide toward said aperture, a dial normally closing said aperture and movable with said carriage, a clock movement mounted upon said carriage having a key directed toward said aperture, said movement and key being normally housed within said casing, and means for sliding said carriage aperture-ward a sufficient distance to present said key at the opening vacated by said dial. 90

3. A clock including a casing apertured at one side, a carriage within said casing mounted to slide toward said aperture, a dial normally closing said aperture movable with said carriage, a clock movement mounted upon said carriage having the hand supporting elements passing through said dial, a winding key for said movement directed toward said aperture, said movement and key being normally housed within said casing, and means for sliding said carriage aperture-ward a sufficient distance to present said key at the opening vacated by said dial. 95

4. A clock including a casing apertured at one side, a carriage within said casing mounted to slide toward said aperture, a dial normally closing said aperture and movable with said carriage, a clock movement mounted upon said carriage, said movement being normally housed within said casing, and means for sliding said carriage aperture-ward a sufficient distance to present the movement forwardly adjacent the opening vacated by said dial. 105

5. A clock including a casing apertured at one side, a carriage in said casing mounted to slide toward said aperture, a light-transmitting dial normally closing said aperture and movable with said carriage, a clock movement mounted upon said carriage, a source of illumination also mounted upon said carriage intermediate said clock movement and dial, said movement and source of illumination being normally housed within said casing, and means for sliding said carriage aperture-ward a sufficient distance to carry said source of illumination outside of the opening vacated by said dial. 120

6. A clock including a casing apertured

at one side, a carriage within said casing mounted to slide toward said aperture, a light-transmitting dial normally closing said aperture and movable with said carriage, a clock movement mounted upon said carriage, a source of illumination also mounted upon said carriage intermediate said clock movement and said dial, a winding key for said clock movement directed toward said aperture, said movement, key, and source of illumination being normally housed within said casing, and means for sliding said carriage aperture-ward a sufficient distance to render said key and source 10 of illumination accessible at the opening vacated by said dial.

7. A clock including a casing apertured at one side, a carriage within said casing mounted to slide toward said aperture, a light-transmitting dial normally closing said aperture and movable with said carriage, a clock movement upon said carriage having the hand supporting elements passing through said dial, a source of illumination also mounted upon said carriage intermediate said clock movement and dial, said movement and source of illumination being

normally housed within said casing, and means for sliding said carriage aperture-ward a sufficient distance to carry said 30 source of illumination outside of the opening vacated by said dial.

8. A clock including a casing apertured at one side, a carriage within said casing mounted to slide toward said aperture, a light-transmitting dial normally closing said aperture and movable with said carriage, a clock movement mounted upon said carriage and having its hand supporting elements passing through said dial, a source 40 of illumination also mounted upon said carriage intermediate said clock movement and said dial, a winding key for said clock movement directed toward said aperture, said movement, key and source of illumination being normally housed within said casing, and means for sliding said carriage aperture-ward a sufficient distance to render said key and source of illumination accessible 45 at the opening vacated by said dial.

In testimony whereof I have hereunto set my hand.

MAUD C. FOX.
